VACUUM BALL HOLDING AND PROPELLING DEVICE

Richard N. Carver, Erie, Pa., assignor to
Louis Marx & Co., Inc.

Filed Apr. 19, 1971, Ser. No. 135,531

Term of patent 14 years

Int. Cl. D21—01

U.S. Cl. D34—15

FIG. 1 is a front perspective view of a vacuum ball holding and propelling device in accordance with my new design;

FIG. 2 is a top elevational view thereof;

FIG. 3 is a side elevational view thereof;

FIG. 4 is a front view thereof;

FIG. 5 is a rear view thereof.

I claim:

The ornamental design for vacuum ball holding and propelling device, as shown.
